PULL-OUT HANGROD

Earl L. Clouse, Grand Rapids, Mich., assignor to
 Grand Rapids Store Equipment Company,
 Grand Rapids, Mich., a corporation of Michigan

Application February 24, 1941, Serial No. 380,213

8 Claims. (Cl. 211—123)

This invention relates to an extensible hangrod and particularly a detachable mounting therefor of simple, novel, practical and efficient character.

I have heretofore made application for patent, Serial No. 312,872, filed January 8, 1940, which will issue as Patent No. 2,233,733, on March 4, 1941, for Mounting for hangrods.

A rod carried on the mountings is located within and extends between the ends of a case or cabinet and on such rod garment hangers from which garments may be suspended are placed. The mountings are adjustable in height to any one of a large number of positions. The present invention is concerned with an extensible pull-out rod which may be mounted within and at an end of the display case or cabinet, and extended outwardly so that a garment taken from the main rod, after being examined need not be put back within the cabinet, but be supported by placing its hanger on the extended pull-out rod of the present invention.

In the course of displaying garments which a customer is examining with a view to purchasing, several of the garments may be tentatively selected and hung from the extensible pull-out rod, and eventually the customers have a comparatively few from which to choose, and which few have been earlier selected from the large number housed by the cabinet.

The present invention is concerned with an extensible rod of the character noted, and with a means for detachably and adjustably connecting it with the same supporting means used and upon which the mountings for the main hangrod are adjustably supported. The present extensible rod will be mounted a short distance above the main supporting rod and when the carrying mountings of the main rod are lowered or raised in the cabinet, the extensible rod construction of the present invention may be correspondingly adjusted if desired. The invention is of a simple and economical character and with the means which I have devised may be instantly applied and latched securely in place, the latches used being releasable so that the structure may be removed entirely or for replacement in another position.

An understanding of the invention may be had from the following description taken in connection with the accompanying drawing, in which,

Fig. 1 is a fragmentary horizontal section through one end of a case or cabinet showing the extension rod of my invention mounted at the

inner side of a cabinet and within the cabinet in retracted position.

Fig. 2 is a similar view showing the device extended beyond the front of the cabinet.

5 Fig. 3 is a side elevation of the construction shown in Fig. 2.

Fig. 4 is a fragmentary front elevation illustrating the manner in which the extensible rod carrying sleeve is supported at each end on and within the end of a merchandising holding case.

10 Fig. 5 is a fragmentary transverse section showing in detail the releasable latching engagement of the extensible hangrod with its supports, and

15 Fig. 6 is a fragmentary perspective view of one end of the extensible rod sleeve in which the immediate extensible rod portion is slidably mounted for longitudinal movement.

Like reference characters refer to like parts in 20 the different figures of the drawing.

The case or cabinet with which this invention is used has vertical ends 1 spaced horizontally from each other. The case also has a back and the usual base and top. When the hangrod embodies this invention is used with a display case 25 the front closure is usually omitted.

At the inner sides of the vertical ends of the case a plurality, usually three, supporting members 2 are pivoted, located in spaced relation to 30 each other and disposed vertically and embedded in the ends of the case. Such supporting members 2 preferably are made in channel form from sheet metal, having spaced apart sides 3 integrally connected by a U-bend and terminating 35 in oppositely turned flanges 4. The U-shaped supporting members are inserted and held in vertical slots cut at the inner sides of the ends 1 of the case. Each of the sides 3 thereof is provided with a large number of vertically spaced tongues 40 5 struck inwardly toward each other, those at one side extending downwardly and inwardly and at the other upwardly and inwardly, so that the tongues overlap in pairs and thereby make a continuous series of spaced apart transverse supporting elements between the sides 3 of the channel members.

As previously stated, these channel members 2 in practice are preferably used three in number on each end of the case, one being adjacent the 50 front edge of the case, one near the rear thereof and the remaining one midway between. It is on these supporting elements that the hanger rod mounting of my patent previously referred to are detachably held as fully shown and described 55 in such patent.

With the present invention a tube 6 of sheet metal is provided of a length substantially equal to the distance between the front and middle supporting members 2 described. The tube at each end has permanently secured therewith a flat metal plate 7 which at one side has a lateral extension 8 terminating in an upwardly extending finger 9 (Fig. 6). The plate 7 is extended downwardly and offset to provide an arm 10 on which a manually operable latch is pivotally mounted. The latch is made of flat metal and has an arm 11 terminating in a latching dog 12 and includes a second arm 13 located at an angle to the arm 11 and integral therewith. At the juncture of the two arms 11 and 13, the pivot 14 passes therethrough and is carried at the lower end of the arm 10.

Such sleeve with the attaching devices described, one at each end, is adapted to be operatively connected with two of the pairs of supporting tongues 5, one located directly over the other, while the latching dog is adapted to be releasably engaged with a third of the pairs of tongues 5 next below as shown in Fig. 5. The hook 9 engages with the uppermost of the tongues 5 selected. The lower edge of the lateral extension 8 rests upon the next tongues 5 below, while the latching hook 12 is turned to engage with the adjacent tongues 5 next below. The parts 8 and 9 and the latching dog are in the same vertical plane. The arm 13 is manually operated to turn the latching dog to the holding position, shown in Fig. 5, or to turn it back to releasing position as shown in Fig. 6.

An elongated rod 15 approximately twice the length of the sleeve 6 is passed therethrough and mounted for free slidable movement. At its rear end it has a stop provided by a washer held by a screw as at 16. At its front end it has a knob 17 to be grasped for pulling the rod 15 outward from the position shown in Fig. 1 to that shown in Figs. 2 and 3.

In the outer position, garment hangers with garments thereon may be suspended from the extended rod member 15 and in such case will be disposed at right angles to the main supply of garments suspended from the main longitudinal hangrod in the case. Garments initially or tentatively selected for further examination will be removed from the main hangrod and suspended from the extended member 15.

It is evident that the extensible hangrod construction which I have described is one which is very quickly and easily released to either be removed in its entirety from the cabinet or adjusted to a new position. The construction while of a simple nature has proven very practical and useful.

The invention is defined in the appended claims and is to be considered comprehensive of all forms of structure coming within their scope.

I claim:

1. A pull-out hangrod comprising, an elongated sleeve, a rod mounted for slidable longitudinal movement therein, members of flat metal connected one at each end of the sleeve and dis-

posed transversely thereof, each having a laterally offset section terminating in an upwardly extending finger providing an upwardly open hook and also having a downwardly extending arm, and a latch pivotally mounted on each of said downwardly extending arms, said latch having a downwardly open hook positioned in opposition to the first mentioned hook.

2. A pull-out hangrod comprising, an elongated horizontal sleeve, a rod longer than the sleeve extending therethrough for slideable movement, stops at opposite ends of the rod to engage against opposite ends of the sleeve, connecting devices secured one at each end of the sleeve, each provided with a fixed upwardly extending hook and a pivotally mounted downwardly extending hook below the first mentioned hook, as and for the purposes specified.

3. A pull-out hangrod comprising an elongated horizontal sleeve, a rod longer than the sleeve extending therethrough and slidably mounted therein for longitudinal movement, stops at opposite ends of the rod to engage against opposite ends of the sleeve, transverse plates connected to opposite ends of the sleeve and through which the ends of the sleeve pass, each of said plates at one side having a lateral extension terminating in an upwardly turned finger to provide a fixed hook open at its upper side, and each of said plates having an arm extending downwardly below the sleeve, and a lever pivotally mounted at the lower portion of each arm, said lever having two arms located at an angle to each other, one being for manual operation of the lever and the other terminating in a downwardly turned hook, as specified.

4. A construction containing the elements in combination defined in claim 3, each of said arms on the plate being offset from the plane of the plate a distance equal substantially to the thickness of said plate whereby said first mentioned hooks and associated levers are disposed in substantially the same vertical planes.

5. A pull-out hangrod comprising, an elongated sleeve, a rod extending therethrough and slidably mounted therein for longitudinal movement, and supports connected with said sleeve each including a thin hook member opening upwardly and extending transversely of said sleeve.

6. The combination of elements defined in claim 5, combined with a latch member pivotally mounted on said support below said hook.

7. A pull-out hangrod comprising, an elongated sleeve, a rod extending therethrough for slideable movement, connecting devices secured to said sleeve, each provided with an upward extending hook and a downward extending arm and a second hook pivotally mounted upon said arm.

8. The combination of elements defined in claim 7 in which said downward extending arm is off-set and said second hook is pivotally mounted on said off-set portion whereby the two hooks will be in the same plane.

EARL L. CLOUSE.
